United States Patent Office.

FRANCIS W. CROSBY, OF NEW YORK, N. Y.

Letters Patent No. 63,221, dated March 26, 1867; antedated March 19, 1867.

IMPROVED AMALGAMATOR.

The Schedule referred to in these Letters Patent and making part of the same.

TO ALL WHOM IT MAY CONCERN:

Be it known that I, FRANCIS W. CROSBY, of the city, county, and State of New York, have invented a new and improved Apparatus for the Amalgamation of Gold and Silver Ores; and I do hereby declare the following to be a full and exact description thereof, reference being had to the accompanying drawings, forming a part of this specification, and in which a vertical central section is represented as drawn through my improved apparatus, showing its several features and the details thereof.

The nature of my invention consists in the trituration of ores when submerged in a bath of quicksilver or molten lead, and also in the combination for this purpose of grinding surfaces with the base or bottom of an extended, upright, ore-supplying cylinder or chamber and the interior of an enclosing amalgam vessel formed to contain quicksilver or molten lead.

The feeding or ore-supplying chamber A of my improved apparatus is constructed in the form of a long, upright, cylindrical vessel, gradually enlarging in diameter from top to bottom. This supplying chamber A is supported by suitable braces *a*, or otherwise, over and partially within an amalgamating vessel, B, which encloses its lower end. This lower end fits closely within an opening formed in the centre of a circular plate, C, so that the ore in the chamber A may fall through the plate C upon a lower grinding plate, D, placed beneath it. This lower plate D is equal in diameter to the upper annular plate C, and is secured to an upright shaft, E, whose lower end is stepped and pivoted in a suitable bearing in the bottom of the amalgamating vessel B, and which extends thence vertically up through the centre of the ore-supplying cylinder A. The opposite faces of the stationary annular grinding plate C, and of the lower revolving plate D, are placed in close proximity to each other, and I prefer so to form them as that they shall incline upwardly in every direction from centre to circumference, the inclination of the lower revolving plate D being made somewhat greater than that of the stationary plate C, so that the interval left between them shall diminish in approaching their circumference. The shaft E and its attached grinding plate D are made to revolve at pleasure by means of a pulley, F, and a belt communicating with any suitable motive power. The upper side of the encircling plate C, around the lower end of the supplying chamber or cylinder A, is sloped upwardly towards its sides, as seen in the drawing. In order to adapt my apparatus to the use of molten lead as an amalgamating material, I propose to set the vessel A within a suitable enclosing furnace, H, constructed of masonry or otherwise, having a grate, K, and ash-pit, M, of any effective form. In such case I afford a support to the centre of the amalgamating vessel by means of a central hollow column, O, of fire-clay brick, or other proper material, and by opening a communication between the hollow central space of the column and the outer air, prevent the seat of the bearing for the shaft E, in the centre of the bottom of the amalgamating vessel, from becoming over-heated.

In operating with my improved apparatus, the amalgamating vessel is filled with quicksilver or with molten lead, until the lower end of the ore-supplying cylinder is fully immersed, as indicated by the yellow lines in the drawing. The supplying cylinder A is then filled with pulverized ore, and the shaft E put in revolution. The weight of the column of ore in the cylinder A will force the lower portion thereof down into the amalgamating bath, and upon the revolving plate D, whose motion will diffuse the particles of the ore and force them out radially between the surfaces of the plates D and C. These plates will gradually rub and grind each particle of the ore as it passes out between them to their circumference, whilst the ore is in direct contact with the quicksilver or lead in the vessel, and thus the complete amalgamation of the precious metal in the ore is perfectly insured. So soon as the particles of ore have passed out from between the grinding plates, their comparative buoyancy will cause them to rise at once to the surface of the quicksilver or lead in the space between the supplying cylinder and the inside of the amalgamating vessel, and to work out over the sides of said vessel. The form of the interior of the ore-supplying cylinder, by which its internal diameter increases towards the bottom thereof, prevents the ore from packing therein. Where molten lead is used, its oxidation is prevented by the layer of refuse ore covering it in the space between the supplying cylinder and the inner side of the amalgamating vessel, as well as by the mass of ore within said cylinder. It is kept in a proper state of fusion by the fire in the furnace surrounding the amalgamating vessel. By means of the peculiar form of my amalgamating vessel B, in combination with the ore-supplying cylinder and the grinding disks, the ore is so retarded in its passage through the molten lead, and the grinding action of the disks causes such an intimate contact of

the one with the other, as that but a comparatively small quantity of the lead is required, whilst the smallest possible surface thereof is exposed to oxidation.

Having thus fully described my invention, what I claim therein as new, and desire to secure by Letters Patent, is—

Grinding or triturating pulverized ores when submerged in a bath of quicksilver or molten lead, substantially in the manner and for the purpose herein set forth.

I claim, also, the combination of one or more grinding plates or surfaces with the bottom of an ore-supplying chamber and an enclosing bath of quicksilver or molten lead, substantially in the manner and for the purpose herein specified.

I claim, also, the combination of a hollow column or pillar, O, with the bottom of an amalgamating vessel, B, and an enclosing furnace, H, substantially in the manner and for the purpose herein set forth.

The foregoing specification of my improved amalgamating apparatus signed by me this second day of April, A. D. 1866.

FRANCIS W. CROSBY.
